(57) **CLAIM**

The ornamental design for a handle for rake, as shown and described.

DESCRIPTION

FIG. 1 is a front elevational view of the design for a handle for rake;

FIG. 2 is a rear elevational view of the design of FIG. 1;

FIG. 3 is a left side elevational view of the design of FIG. 1;

FIG. 4 is a right side elevational view of the design of FIG. 1;

FIG. 5 is a top plan view of the design of FIG. 1;

FIG. 6 is a bottom plan view of the design of FIG. 1;

FIG. 7 is a top, front, right side perspective view of the design of FIG. 1; and,

FIG. 8 is an environmental, reduced scale perspective view thereof with the broken line showing of a rake head being for illustrative purposes only and forming no part of the claimed design.

The surface(s) or portion(s) of the article not shown in the drawing or described in the specification form(s) no part of the claimed design.
